HALVOR O. HEM

John Marshall
ATTORNEY

UNITED STATES PATENT OFFICE

HALVOR O. HEM, OF TOLEDO, OHIO, ASSIGNOR TO TOLEDO SCALE MANUFACTURING COMPANY, OF TOLEDO, OHIO, A CORPORATION OF NEW JERSEY

COIN OPERATED SCALE

Application filed November 26, 1929. Serial No. 409,955.

This invention relates to improvements in weighing scales and particularly to scales whose mechanism is locked until released by the introduction of a coin. Scales of this type are usually provided with a receptacle for receiving the coins and means for guiding the coins from the unlocking mechanism to this receptacle. These coin receptacles are usually located in the bottom of the column or other scale support and as these scales are often stationed on the street where they are exposed to the weather, it is occasionally inconvenient to remove the coins. Manufacturing companies who build coin operated scales for export are also handicapped by the fact that the coins vary considerably in size in the different countries and therefore must manufacture coin controlled mechanisms in several sizes to accommodate the different coins.

One of the principal objects of this invention is the provision of means for receiving and guiding coins of various sizes to the coin receptacle.

Another object of this invention is the provision of means for collecting a great number of coins.

A further object is the provision of means whereby the coins receptacle may be emptied without difficulty and without the loss of coins, directly into a bag or other container carried by the collector.

A still further object is the provision of means for guiding the coins after they have released the weighing mechanism.

Other objects and advantages will be apparent from the following description in which reference is had to the accompanying drawing illustrating a preferred embodiment of the invention and wherein similar reference numerals designate similar parts throughout the several views.

Figure I is a front elevation of a coin controlled person weighing scale embodying this invention.

Figure II is a fragmentary sectional view substantially along the line II-II of Figure I illustrating the construction of the coin receptacle.

Referring to the drawing in detail, the

scale in which the invention is shown embodied, is the well known Toledo person weighing scale fully described and illustrated in United States Patent No. 1,685,779 to H. O. Hem, and I will therefore describe it only in so far as is necessary to properly explain the invention.

A base 1 supports and houses suitable lever mechanism (not shown) on which a platform 2 is suitably mounted. A column 3 is supported on the rear of the base 1 and contains a portion of the weighing mechanism and supports on its upper end a shell-like member 4 in which the coin controlled releasing mechanism is located. A substantially watch-case-shaped casing 5 is secured to the top of the shell-like member 4 and contains the load counterbalancing mechanism 6. This load counterbalancing mechanism 6 is operatively connected to an indicating hand 7 which co-operates with the indicia 8 printed or etched on a stationary chart 9 to indicate the weight of loads placed on the platform. The scale is locked against operation until a coin 14 is introduced into the coin slot 10 and the plunger 11 is pushed inwardly which co-operates with the coin in releasing the locking mechanism and permitting the counterbalancing and indicating mechanisms to function. It has also been found difficult to provide coin operated scales with a receptacle for holding a sufficiently large number of coins and scales of this type, when located near busy street intersections or large department stores, had to be emptied of their contents at frequent intervals. In the present invention, provision has been made for converting a large portion of the column into a coin receptacle in which a large number of coins may collect, and which need only be emptied at infrequent intervals, effecting a great economy. This is accomplished by providing inwardly extending partitions 21 in the column to which an emptying funnel 22 is attached.

The load supporting lever mechanism which is housed in the base 1 is connected by a connecting rod 30 to the counterbalancing mechanism 6. This rod release extends through that portion of the column which has

been converted to a coin receptacle. To prevent the coins from contacting the rod, it is incased for a portion of its length by a tube 31, which does not form a moving part, nor 5 does it contact one.

The funnel 22 has an opening in its front which is normally closed by a door 23. This door is pivoted at 24 to the funnel and is provided with sides 25 which form a chute, 10 for the coins, when opened. A latch 26 secured to the funnel normally retains the door 23 in a closed position. Access to the funnel is had through an opening 27 in the column 3 which is closed by a cover 28 and which is 15 locked by a lock 29. When the coin box is to be emptied, the operator unlocks the lock 29 which permits him to remove the column opening cover 28. The latch 26 is now exposed and upon turning this latch, the door 20 23 may be swung into the position as shown by the dotted lines in Figure II. This door with the sides 25 forms a chute which extends through the opening and away from the column so that a bag or a box may be held directly underneath into which the coins will 25 flow by gravity.

It will be seen that the described construction greatly facilitates the emptying of the receptacle. Heretofore the box or coin receptacle formed a separate piece which had to be removed, usually these receptacles were of small size, and when full, coins were easily lost when being removed. In the present invention that portion of the column, above 30 the coin funnel 22 and up to the point where the dashpot and other mechanism is located, is converted into a coin receptacle which is adapted to hold a great number of coins and by means of the described mechanism may 35 be easily emptied. It will be seen from the foregoing description that all of the objects 40 are efficiently attained.

The embodiment of my invention is to be regarded as illustrative only, and it is to be 45 understood that the invention is susceptible to variation, modification, and change within the spirit and scope of the subjoined claims.

Having described my invention, I claim:

In a coin released weighing scale, in combination, an upwardly extending hollow standard and partitioning means within said standard forming a receptacle for coins, said partition means including an inclined chute positioned interiorly of said standard, said 50 chute having an opening and means for closing said opening, said closing means forming an extension of said interiorly disposed chute and extending through an aperture in said standard, when opened.

60 HALVOR O. HEM.
